United States Patent Office

Des. 209,047
Patented Oct. 31, 1967

209,047

OUTDOOR BENCH

Luis F. Villa, 1727 Moravian St.,
Philadelphia, Pa. 19103

Filed July 12, 1966, Ser. No. 3,050

Term of patent 14 years

(Cl. D15—11)

FIGURE 1 is a plan view showing my new design;
FIGURE 2 is an elevational view taken from the rear
thereof;

FIGURE 3 is an elevational view taken from the front
thereof;

FIGURE 4 is an elevational view taken from the left
side thereof; and

FIGURE 5 is an elevational view taken from the right
side thereof.

The base of my design is substantially plain and un-
ornamented.

I claim:

The ornamented design for an outdoor bench, as shown
and described.
